UNITED STATES PATENT OFFICE.

HERMAN ZAHNOW, OF BALFOUR, NORTH DAKOTA.

WINDMILL.

1,349,182.

Specification of Letters Patent. Patented Aug. 10, 1920.

Application filed June 30, 1919. Serial No. 307,824.

To all whom it may concern:

Be it known that I, HERMAN ZAHNOW, a citizen of the United States, residing at Balfour, in the county of McHenry, State of North Dakota, have invented certain new and useful Improvements in Windmills; and I do hereby declare the following to be a full, clear, and exact description of the invention, such as will enable others skilled in the art to which it appertains to make and use the same.

This invention relates to new and useful improvements in windmills, and particularly to the type of vertical wheel windmills.

15 One object of the present invention is to provide a novel and improved windmill which will automatically collapse when the wind pressure becomes too great so that racing will be prevented.

20 Another object is to provide a novel and improved structure of this character; the wheels are normally side-by-side in the same plane and so mounted that when the wind pressure becomes too great both wheels will 25 swing rearwardly at opposite sides of the vane or tail.

A further object is to provide novel and improved means for automatically restoring the wheels to a position toward the wind 30 when the pressure has been reduced to the point of safety.

Other objects and advantages will be apparent from the following description when taken in connection with the accompanying 35 drawings.

In the drawings:

Figure 1 is a front elevation of the windmill in normal running position.

40 Fig. 2 is a top plan view of the mill in the position of Fig. 1.

Fig. 3 is a top plan view of the mill when the wheels have been swung backwardly at the sides of the vane.

45 Fig. 4 is an enlarged vertical sectional view taken on the line 4—4 of Fig. 1, through the vertical standard and shaft.

Fig. 5 is a rear elevation of the windmill in the position of Fig. 1, the lower portion of the tower being broken away.

50 Fig. 6 is a sectional view taken on the line 6—6 of Fig. 5 showing the construction of one of the brace arms.

Fig. 7 is a vertical transverse sectional view taken on the line 7—7 of Fig. 2 showing the arrangement of the wheel supporting 55 arms.

Referring particularly to the accompanying drawings, 10 represents a skeleton tower of the type usually provided for windmills and having the vertical tubular member 11 disposed longitudinally therethrough, which has the operating shaft 12 disposed within it. On the upper end of this shaft there is mounted the double-faced bevel pinion 13. Secured on the upper portion of the shaft 11 and the member 11, at vertically spaced points, are the collars 14 and 15, and carried by these collars and extending at right angles from the tubular member, are the horizontal arms 16 and 17, the rear ends of which carry the vane or tail 18 of the windmill. Rotatably engaged on the member 11, above the lower collar 15, is a collar 19, and pivotally connected to this collar 19 is the bifurcated lower end of the brace arm 20. Another collar 21 is loosely mounted on the member 11, above the collar 19, and has the lower end of the other brace arm 22 pivotally connected thereto. The collar 14 acts as a stop collar to support the collars 23 and 24 of the supporting arms 25 and 26 which extend horizontally outwardly from the said collars. Loosely engaged on the upper end of the shaft 12, above the upper end of the tubular member 11, is a T-coupling 27, and engaged in the horizontal portion thereof is the inner end of the horizontal shaft 28, the outer end being rotatably supported in a bearing bracket 29 carried by the outer portion of the arm 26. The inner portion of the shaft 28 has fixed thereto a pinion 29 which meshes with the toothed upper face of the pinion 13, while the outer end is provided with a bevel pinion 30 which meshes with a bevel pinion 31 carried by the hub 32 of the windwheel 33. This hub is supported on a shaft 34 carried by and connected to the outer ends of the arms 20 and 26. Carried by the end portions of the arm 25 are the bearing brackets 35 in which is rotatably supported the shaft 36. The shaft has on its inner end a bevel pinion 37 which meshes with the lower toothed face of the pinion 13, while on the outer end there is mounted a bevel pinion 38 meshing with the pinion 39 carried by the hub 40 of the other wheel 41. This hub 40 is supported on a shaft or axle 42 carried by the upper ends of the arms 22 and 25. Each of the hubs has the radial spokes 43 to which are secured radial arms 44, and carried by these arms is a ring 45, the blades of the

wheel, shown at 46, being connected to this ring and to the hub.

Mounted in the lower portion of the tower is a spring actuated drum 47, and secured to this drum, and wound thereon, is one end of a chain 48 which extends upwardly over a pulley 49, on the upper portion of the tower where it is secured to a block 50 slidably mounted on the upper arm 16 of the tail or vane. This block is pivotally connected to the arms 25 and 26 by means of the links 51, whereby, when the wind pressure becomes too great for the wheels the wheels and the arms 25 and 26 will be swung rearwardly toward the opposite sides of the tail or vane, and by reason of the connection of the links 51 the block 50 will be pushed rearwardly on the arm or rod 16, with the result that the chain 48 will be pulled upwardly thereby and unwound from the drum, against the tension of the spring. Thus the spring of the drum is of a strength to hold the wheels in the face of a wind of a certain pressure, and when this pressure is exceeded the spring will yield and permit the collapsing of the mill so that the wheels will not race and be liable to damage or breakage. When the wind pressure is reduced to the safety point for the wheels, the spring drum will automatically wind up the chain 48, pulling the block 50 inwardly toward the shaft 12, and restoring the wheels to their operative position by the pushing action of the links 51. A brace 52 extends from the upper arm 16 to the tubular member 11 where it is connected to a collar 53 carried by and rotatable with the tubular member. Thus the various arms, the vane, and the wheels are capable of swinging axially on the shaft 12,

thus permitting the wheels to present themselves to the wind at all times.

There is thus provided an automatic windwheel which, when the wind pressure becomes too great for the wheels, will collapse to move the wheels out of the path of the wind and thus prevent damage thereto. The structure also provides for the return of the wheels to normal operative position, in the eye of the wind, when the wind pressure is reduced to the safety point.

What is claimed is:

In a windmill, the combination with a tower supporting an upright tubular member, a shaft rotatably mounted in the latter, and a double faced beveled pinion on the shaft; of collars on said shaft, horizontal arms and oblique braces projecting from said collars to both sides of the shaft, wind wheels mounted in the outer ends of said arms, shafts connected with them and leading inward and having beveled pinions meshing with opposite faces of that mentioned, arms projecting to the rear from certain of said collars and carrying a vane, a block slidably mounted on one of said arms, links pivotally connecting it with said lateral arms, and means drawing the block forward and swinging the lateral arms into position to hold the wheels normally in a single plane, said means yielding under excess wind pressure to permit the wheels to swing back into parallel planes.

In testimony whereof, I affix my signature in the presence of two witnesses.

HERMAN ZAHNOW.
